CIRCUIT CONTROLLER

Stanley S. Green, La Fayette, Ind., assignor to
 Duncan Electric Manufacturing Company, La.
 Fayette, Ind., a corporation of Illinois

Application March 6, 1933, Serial No. 659,775

26 Claims. (Cl. 200—113)

This invention relates to circuit controllers and more particularly to liquid conductor current-limiting circuit controllers. In the illustrated form the invention comprises a casing having 5 therein a control tube, electrodes on opposite sides of the control tube, and a liquid conductor such as mercury to connect the electrodes through the control tube, the construction being such that upon an overload the mercury in the 10 control tube is vaporized, thereby breaking the circuit. The circuit may be re-established by turning the controller to the off position and back to the on position, these movements flowing the mercury back in the control tube. Circuit controllers of this type have been the subject 15 matter of various applications made by the present inventor, the last of which was filed May 6, 1931 (Serial Number 535,401), in which the former applications are listed. The present application is concerned with an improved circuit controller of this type, and includes numerous 20 refinements.

Numerous objects are accomplished by this invention, including the prevention of current 25 leaks along the surface of the casing, the provision of a control tube material which is chemically stable under arcing conditions, the minimizing of arcing in the control tube, the provision of more dependable mercury feeding means, 30 the simplification of structure and construction, and the provision of an indicator for showing whether or not the circuit breaker has been blown by an overload, i. e., whether or not an overload has caused it to break the circuit which 35 it controls.

With these and various other objects in view, the invention may consist of certain novel features of construction and operation, as will be 40 more fully described and particularly pointed out in the specification, drawing and claims appended hereto.

In the drawing, which illustrates an embodiment of the device, and wherein like reference characters are used to designate like parts,

45 Figure 1 is a perspective view of one embodiment of this invention without the indicator, and showing the controller unit slightly turned from its normal on position;

50 Figure 2 is a vertical view partly in section of the structure in Figure 1, showing the controller in its normal on position;

55 Figure 3 is a view similar to Figure 2, but showing the controller in the reverse position, and illustrating different details;

Figure 4 is a vertical transverse section substantially through the line 4—4 of Figure 2;

Figure 5 is a view similar to Figure 4 but taken substantially through the line 5—5 of Figure 2;

Figure 6 is a diagrammatic illustration of the connection of the indicator to the controller.

Although my invention may take many forms, only one has been chosen for illustration. In this form, the assembly comprises the base 2 and the controller 4 pivotally mounted thereon and electrically connected thereto. The structure of the mounting was fully set forth in the application Serial Number 535,401 mentioned above, and therefore may be described here with brevity. The main support is furnished through the support terminal 6 to which is pivoted a conductor link 7 which is rigidly secured by a screw or otherwise to a lead-in stud 8. This furnishes one path of current to the controller, and the other path extends through the terminal connector 10 to 20 which is pivoted the connector link 11 which is rigidly secured as by a screw to the second lead-in stud 12. It may be seen that the only pivotal connections are between the members 6 and 7 and the members 10 and 11. Both of these connections include relatively large areas of sliding contact, and a firm connection may be insured in each instance by including a spring washer (not shown) on the pivot pin to press one of the sliding members against the other. The terminal supports 6 and 10 are of course secured as by rivets to the base 2 and are provided with suitable connection screws 14 and 15 as shown, for connecting the controller in the circuit to be controlled.

35 The general construction of the controller 4 includes a casing made up of a rear half 16 and the cover half 18, both preferably molded from an insulating material such as that known commercially as "Bakelite". These two parts are provided with telescoping flanges 20 and are preferably sealed together as is hereinafter described. The cover member 18 may include an upstanding ring 22 which may fit an opening in a metal switch box, a handle 23, and suitable wording 40 such as the words "Off" and "On" and any other data that may be desired. The rear casing half 16 has molded into it the lead-in studs and an arc by-pass stud described below, which may all have knurled surfaces for tighter engagement 45 of the "Bakelite".

50 Within the casing is a control unit which may be designated in its entirety by the numeral 24. This unit includes the control tube 26, metallic reinforcing jacket 28, the feed tube 30 welded 55

thereto and the insulating coating 32. This control unit is supported by the mating shoulders 34 and 35 formed on the two parts 16 and 18 respectively of the casing which engage the feed tube 30, and also by the cradles 37 and 38 likewise formed on the two parts 16 and 18 of the casing, and which cradles engage the jacket 28 or its coating 32.

The shoulders 34 and 35 are in the nature of extensive partitions and are so shaped as to form a passage 40 which is a continuation of the feed tube 30 and which widens out at its mouth to form a funnel 42.

The lead-in stud 8 extends through the partition 34 and has secured at its end as by a screw, an electrode 44, which electrode is shaped to extend into the feed tube 30, as shown best in Figure 2. The feed tube 30 communicates with a current-limiting bore 46 in the control tube 26, which bore opens into a well 48 in the end of the control tube into which projects a second electrode 50. This second electrode 50 is secured by an elongated screw 52 to the lead-in stud 12, being suitably spaced from the wall of the casing half 16 by the fiber bushing 54 which may be seated against an asbestos washer 56 if desired.

A suitable quantity of liquid conductor such as mercury (and which is referred to hereinafter simply as mercury) is provided within the casing of the controller 4. When the controller is in the off position shown in Figure 3 this mercury runs to the then bottom of the controller as shown in that figure. As the controller is rotated in a clockwise direction from the position shown in Figure 3 to the position shown in Figure 2, the mercury flows into the funnel 42 by which it is fed into the passage 40, from which it flows on into the feed tube 30. From the feed tube 30 the mercury is forced into and through the bore 46 of the control tube 26. For low amperage controllers the bore 46 is necessarily of extremely small diameter and offers considerable resistance to the flow of mercury therethrough. For this reason, it is desirable that the passage 40 be of comparatively small diameter, as shown, so that a comparatively small amount of mercury will fill it to the top, thus providing a considerable hydrostatic head of mercury at the entrance to the bore 46, and the quantity of mercury in the controller should be the amount necessary for this purpose, with perhaps a small reserve in excess thereof. For one form of breaker having a rating of 10 amperes, the diameter of the bore should be approximately .026 inch. To start the mercury into such a bore a head of approximately .67 inch is required. For the sake of dependability, it is preferred that the head of mercury provided be twice this, or approximately one and one-third inches. Commercially this head is desirably provided for all circuit breakers rated for 10 or more amperes, although a much lower head of mercury could be used dependably for circuit breakers of a higher ampere rating. For example, a fifty ampere circuit breaker may have a bore diameter of approximately .098 inch and a .22 inch mercury head would be twice the necessary minimum. Obviously, if a circuit breaker were to be rated for less than 10 amperes, a greater head than one and one-third inches might be desired. The flow of mercury can be facilitated by tapering the bore slightly, so that it is large toward the upper end, i. e., smaller at the end which the mercury enters. Once the mercury has passed entirely through the bore 46 it will continue flowing therethrough

until it reaches a state of equilibrium, usually when the level in the feed tube is the same as the level in the open well 48.

With the mercury in this position it will electrically connect the two electrodes 44 and 50 by a path extending longitudinally through the bore 46. As fully explained in the prior application referred to, a current in excess of that for which the bore 46 is calibrated would generate heat in the mercury faster than it is dissipated through the control tube 26 and through the mercury columns and will therefore raise the temperature of the mercury in the bore 46 until the same vaporizes. The vaporization of the mercury in the bore will expel some of the mercury from the bore, with the result that there will be a gap in the mercury column between the electrodes 44 and 50 so that the circuit will be broken between these electrodes. For the sake of simplicity this phenomenon will be referred to as the blowing of the controller, since it corresponds to the blowing of a fuse.

It is desirable that the feed tube 30 extend at an angle to the bore 46 of the control tube as shown, and that it make a mercury-tight connection therewith, so that once the bore 46 has been filled with mercury it will be impossible for mercury to flow therefrom by gravity. In other words, the feed tube and control tube together should comprise an inner container so shaped as to retain mercury therein indefinitely, until it is spilled out by manually turning the controller, or until it is blown out by an overload. Because of the explosive force of severe overloads, it is necessary that the feed tube 30 be strongly secured to the control tube 26. For these reasons, the bias butt-welding illustrated in Figure 2 is preferred. As is clear from that figure, the feed tube, which is generally curved throughout its length, is severed at its bottom end at a sharp angle. This biased end may then be butt-welded to the corresponding portion of the jacket 28 either by electricity or otherwise. The hole through the jacket 28 which permits the mercury to flow from the feed tube to the bore may be formed either before or after the butt-welding. It may be explained that the jacket is previously formed from a flat piece of sheet iron, as by drawing. The discharge end of the iron jacket should be thoroughly insulated to prevent arcing, for reasons described below. There are various forms of insulation that may be used, such as porcelain cement, vitreous enamel, or sleeves of bakelite or mica. It is preferred, however, that the insulation be provided by winding asbestos tape around the end of the jacket in the position shown, soaking this tape in some such material as those known as bakelite lacquer or glyptal lacquer. Afterwards the unit should be thoroughly baked. Such an insulation is easier to apply than the porcelain cement or vitreous enamel and will withstand the temperature to which it is subjected, since the control tube 26 insulates the jacket from the high temperatures occasionally sustained in the bore 46 of the control tube.

Preservation of accuracy

Delicate testings under conditions more severe than those ordinarily encountered commercially have demonstrated the fact that it is possible for the current capacity of such a circuit controller to vary slightly with continued use. Although such variations would probably never be enough to be detrimental commercially, it is obviously

preferable that they be eliminated, or at least minimized to a point where even extraordinary commercial conditions cannot cause a substantial change. There are various causes that might contribute to variations of current carrying capacity. One of these is a change in the purity of the mercury and the change in the contact resistance between the mercury and the electrodes which this is likely to cause. Such impurities may also cause slight changes in the resistance of the mercury itself. Obviously changes in electrical resistance in the controller, whether they be increases or decreases, change the amount of heat generated in the controller for a given current flow and thus vary the accuracy of rating although such effects are, as mentioned before, small and secondary in their nature. Mercury has a very high affinity for many foreign substances, and it is therefore desirable that such substances be avoided. All of the metal parts which are exposed to the mercury are therefore preferably made of the purest iron that can be obtained commercially. It may be mentioned that this iron is also desirable because it has a higher electrical conductivity than other iron. The lead-in studs 8 and 12 may be made of copper or brass, since they are completely embedded in the "Bakelite" and therefore are not exposed to the mercury.

Another possible cause of variation in current-carrying capacity is the enlargement of the bore 46 of the control tube. It may be explained that this bore is subjected to severe attack; first, by the hot mercury as it is being heated in the bore, and subsequently by mercury vapor after a break has occurred, and to some extent at least by arcing which takes place through such vapor at the moment of the breaking of the current, particularly when a heavy current is broken. The most severe of these attacks is the arcing. Oscillographs taken on the breaker as it opens a heavy current, show clearly that the duration of the electric arc in the bore is very short—of the order of 1/60th of a second in most cases, or even less in others. The arc temperature is such that if long continued it would vaporize surface portions of the control tube bore and thus wear it away by a mechanical or burning action. If such were the case, however, control tube substances having the highest fusing or volatilizing temperatures should exhibit the greatest resistance to such arc erosion or wear. In my experiments I have found this by no means to be always so. Such measurements of bore erosion have been very delicate and tedious because even for hundreds of current interruptions, the amount of erosion in a given bore of a given control tube material is very small. My results indicate that different ceramic substances have quite different erosion-resisting properties and this resistance is more closely connected with its chemical composition than with its physical properties such as the boiling or vaporization point.

At the temperature of the electric arc the chemical reactions between the substance of the control tube and the other substances which may be present becomes of great importance. Among the other substances which can be present in addition to the mercury are the gases enclosed in the circuit breaker chamber such as air, the metal of the electrodes and impurities. It is possible that one of such substances could act as a catalyst or intermediary agent in some chemical action which would deteriorate the walls of the tube. To eliminate as many variables as possi-

ble, experiments have been made using commercially pure iron for electrodes and with all other materials as pure as possible and with control tubes of a wide variety of different substances. The commercial names of some of these substances are herewith listed in approximately the order of their erosion-resisting property: lava, quartz, crolite #445, Pyrex glass, and sillimanite. Of the substances named, I prefer lava, as it has the greatest erosion-resisting properties; lava being the commercial name of an artificially prepared ceramic. It may have slightly differing characteristics and appearance depending upon treatment and source of supply. The grade which I prefer, however, has a body which is composed of talc, which is a silicate of magnesia; feldspar, which is a silicate of aluminum, and a carbon binder. The body, after being formed, is kilned at approximately 2500° F., and the carbon binder burns out. Crolite #445, which is also erosion-resistant, but not to the same degree as lava, also contains magnesia silicate as two-thirds of its total weight is a multiple magnesia silicate comprising silica magnesia and alumina.

Sillimanite, which, among those mentioned, gives the least desirable (although still commercially satisfactory) results, is an aluminum silicate ($Al_2O_3SiO_2$). There are of course many other materials which may be used, but those listed are among the ones known to be satisfactory, at least if pure iron is the only metal exposed, and if pure distilled mercury is used.

Arc minimizing

Since any chemical action or erosion takes place principally during arcing of the mercury, it is of course desirable that the arcing within the control tube should have as short a duration as possible. For this reason an arc shunt is provided. This shunt comprises a plug 60 molded into the casing half 16 and extending therethrough to a point close to the electrode 50 and which is connected to the lead-in stud 8 as by a coiled resistance wire 62 which may be located in a channel 64 provided therefor. In order to carry the current of a severe overload, this wire should be fairly heavy and might conveniently be made of iron. When such an arc shunt is provided, however, it is necessary that it be so restricted as to be harmless and not self-sustaining. Putting a resistance 62 into the circuit is of some aid in this connection. It is preferred, however, that the arc be restricted by covering over all of the plug 60 but its end, with a shield, such as the fiber bushing 66. When such a fiber bushing is used, as shown, so that the exposed area of the plug is kept sufficiently small, the resistance coil 62 may be replaced by a substantially non-resisting conductor. In this form a stud of .078 inch diameter, not closer to the electrode 50 than .30 inch, has been found satisfactory up to 125 volts. Of course these factors are all interrelated, and any arc by-pass stud arrangement that is so restricted that the arc dies quickly would be satisfactory in this respect. There may be considerable leeway beyond the dimensions given by way of example.

It may be explained that, from the standpoint of effectiveness, the shunt will probably function properly as long as it is closer to the electrode 50 than is any other exposed conductor which is connected with the electrode 44. When there is severe overload liquid mercury is blown entirely out of the control tube 26 so that as long as the plug 60 is closer to the electrode 50 than

the length of the bore of the control tube, the arc will take the path of least resistance, and jump between the electrode 50 and the plug 60 rather than through the control tube. This transfers a large part of the harmful arcing during the short period when such arcing exists, outside of the control tube bore where it can do no harm. The plug 60 may be considerably shorter than that shown, and, in fact, may be shorter than the bushing 54. In this event, the plug would be exposed only at its end, and that at the bottom of the hole in the bushing, so that the arc would be well restricted.

It may be noted at this point that it is also necessary to make some provision to prevent arcing between the electrode 50 and the metallic jacket 28. It is for this purpose that the insulating coating 32 is provided. However, if the jacket were electrically isolated, as described in the prior application, Serial Number 535,401, insulation 32 would not be necessary.

Prevention of the surface current leaks

Although the material known as "Bakelite" is admirably suited for the formation of the casing, it is theoretically possible for the exposed surface of this material to become so carbonized that it will conduct current. For this reason it is preferred that there should be no path between the two electrodes or other conductor connected thereto which is entirely along the "Bakelite" surface. It is for this reason that the fiber bushing 54 is provided between the electrode 50 and the "Bakelite" casing. It is not necessary that this bushing be made of fiber, as it may be made of any material which does not become conductive under any circumstances. The material known commercially as "lava" or almost any ceramic material will also answer this purpose. If the electrode 50 does not interlock with the well of the control tube 26 in such manner as to prevent the electrode from swinging outwardly to contact the peripheral wall of the casing, then the bushing 54 should be especially shaped to prevent such movement of the electrode 50, or a special stop of a similar material may be provided elsewhere. The asbestos washer 56 is used simply to provide a mercury-tight seal so that no mercury can get under the fiber bushing 54 and complete a path from the screw 52 to some exposed portion of the "Bakelite" surface.

With such a construction, it is obvious that there is no continuous exposed "Bakelite" surface connecting the two electrodes, nor connecting any conductor which is connected with the electrode 50 to any conductor connected with the electrode 44. The possibility of the occurrence of objectionable surface current-leaks is therefore completely overcome.

Assembly

The final assembly of the parts is quite simple. The two casing halves 16 and 18 are molded according to the standard practice for such "Bakelite" parts, the diameter being approximately 2.5 inches. However, the male half is molded originally to be approximately .008 to .010 inch larger in diameter than the female half. In this condition the male half cannot go into the female half without breaking it. The parts, however, are taken out of the molds after a short period of curing. This is in accordance with the usual practice in molding "Bakelite" for ordinary purposes, since in such practice "Bakelite" is considered cured when taken from the mold. Never-

theless it is subject to material shrinkage by further and complete curing. The male half of the casing is therefore cured substantially to the stabilization point by baking several hours at a temperature in excess of ninety to one hundred degrees cen. which shrinks it sufficiently for it to fit within the female half. Some cement, such as "Bakelite" varnish is then applied to the mating surfaces and also the exterior of the feed tube 30, where it engages the partition members 34, and to the cradles 37 and 38; the female member is pressed in place, and the entire assembly is then baked sufficiently to cure the female half of the casing, which, during the curing process, shrinks down over the male half, as the male half does not shrink as much, if at all, during this final curing. One half of the casing may be provided with a sealing channel 68 which may be filled with the varnish, and which is maintained in a position to retain the varnish during the entire operation. As a final operation, the metal band 70, previously flanged along one edge, is forced over the assembled controller and spun around the other edge into engagement with the controller, as shown best in Figure 5. This band 70 may be made from the same iron that is used for the jacket 28, since in this pure form it will be rust-resisting. As a matter of fact, from the standpoint of commercial practice, it is desirable to form the jacket out of that portion of the metal which is cut from the center of the band. The controller is now ready to be mounted on the base, in accordance with the description of this mounting already given.

35

Indicator

Because of the nature of this controller, there is no visible change to indicate when a controller has been blown. It follows, therefore, that if there are a number of such controllers grouped together it will not be obvious to a person unfamiliar with the circuits, which one of them may be blown out in a given instance. Although this often would be no handicap, since it would merely be necessary to turn the two or three suspected controllers off and then on again, yet, in some instances it may be desirable to have some means for indicating which circuit controller has been blown. For this purpose, the indicator illustrated diagrammatically in Figure 6 may be provided. A contact 74 for this indicator has been illustrated in Figure 1. The indicator proper comprises an extremely small neon or other space discharge tube 76. Such tubes may at the present time be bought commercially and therefore need not be described in detail. It may be mentioned, however, that they comprise two parallel, wire-like electrodes spaced apart only a small fraction of an inch and sealed into a small glass tube which contains a luminous gas at such pressure that a glow may be obtained by small voltages, at least as low as 100 volts, and with infinitesimal currents. Such a glow tube may be connected across the terminals of the controller, as illustrated in Figure 6, one or both of the connections between the glow tube and the controller including a resistance 78 which preferably has a value of around 100,000 ohms. This high resistance limits the current which can pass through the glow tube to such a small value that it is harmless to the tube as well as harmless and negligible in the circuit which is being controlled. As a matter of fact, the glow tube of the indicator described is so sensitive that with alternating current it can be 65 70 75

operated on the capacitance of the wires in an open circuit, so that even though the short circuit no longer exists, and even though the circuit is not otherwise completed the glow tube will glow as a result of the difference of potential between the terminals 14 and 15 of the controller when the mercury column has been interrupted.

Unless special provision were made, such a tube would glow even when the controller was manually turned to the off position. This would ordinarily be objectionable; however, since it is preferred that the indicators glow only when the controller has been blown, not when it has been manually turned off. This result is accomplished according to the present invention by connecting the glow tube through a contact 14 which is only connected with the terminal of the controller when the controller is in an on position. Thus with the circuit controller turned even slightly away from the "on" position, as shown in Figure 1, and as shown diagrammatically in Figure 6, the contact 14 is not connected in the controlled circuit and the glow tube 16 therefore would under no conditions be illuminated. However, if the controller is turned fully to the on position, the connector link 11 engages the contact 14 and completes the circuit to the glow tube 16, but as the glow tube 16 is normally connected across an uninterrupted column of mercury, the potential across the electrodes of the glow tube is substantially zero. On the other hand, if an overload occurs so that the mercury column is broken and the circuit interrupted, the potential across the electrodes of the glow tube will be sufficient to illuminate the same.

It is to be understood that many other embodiments of the invention, including some in improved form, will be apparent, and in the course of time more will be devised by those skilled in the art. It is not desired that this invention be limited to the details described, for its scope includes all such forms or improvements as come within the spirit of the following claims, construed as broadly as the prior art will permit. Especially it is to be noted that although the various novel features described herein have their greatest value when all are used together, yet each may be used without any or with only some of the others.

What is claimed is:

1. A liquid conductor current limiting circuit controller including: a control tube made of heat resisting insulation and having a current limiting bore therewithin, a casing surrounding said control tube and forming an expansion chamber with which said bore communicates suitably for the passage of a liquid into said bore, a pair of electrodes, a suitable quantity of liquid conductor within said container, said container including means for flowing said liquid conductor into said bore and into contact with said electrodes to electrically connect said electrodes lengthwise through said bore, the shape and arrangement of said container and control tube being such that liquid conductor expelled from said control tube by an overload will be prevented from reconnecting said electrodes except upon operation of said means; said controller being characterized by the fact that the portions of said electrodes exposed within said casing when not connected by liquid conductor are insulated from one another by a material which has the quality of maintaining substantially its full insulating qualities in spite of its exposure to high temperatures and to hot gases in contact with its surface.

2. A liquid conductor current limiting circuit controller including: a control tube made of heat resisting insulation and having a current limiting bore therewithin, a casing surrounding said control tube and forming an expansion chamber with which said bore communicates suitably for the passage of a liquid into said bore, a pair of electrodes, a suitable quantity of liquid conductor within said container, said container including means for flowing said liquid conductor into said bore and into contact with said electrodes to electrically connect said electrodes lengthwise through said bore, the shape and arrangement of said container and control tube being such that liquid conductor expelled from said control tube by an overload will be prevented from reconnecting said electrodes except upon operation of said means; said controller being characterized by the fact that the casing is formed in part of a material which becomes conductive under certain conditions, and the lead-in portions of said electrodes exposed within said casing are insulated from one another by a material which has the quality of maintaining substantially its full insulating qualities in spite of its exposure to high temperatures and to hot gases in contact with its surface.

3. A liquid conductor current limiting circuit controller including: a control tube made of heat resisting insulation and having a current limiting bore therewithin, a casing surrounding said control tube and forming an expansion chamber with which said bore communicates suitably for the passage of a liquid into said bore, a pair of electrodes, a suitable quantity of liquid conductor within said container, said container including means for flowing said liquid conductor into said bore and into contact with said electrodes to electrically connect said electrodes lengthwise through said bore, the shape and arrangement of said container and control tube being such that liquid conductor expelled from said control tube by an overload will be prevented from reconnecting said electrodes except upon operation of said means; said controller being characterized by the fact that the casing is formed in part of a material which becomes conductive under certain conditions, and the portions of said electrodes exposed within said casing when not connected by said liquid conductor are insulated from one another by a solid material which retains substantially its full insulating properties during all conditions of service.

4. A liquid conductor current limiting circuit controller including: a control tube made of heat resisting insulation and having a current limiting bore therewithin, a casing surrounding said control tube and forming an expansion chamber with which said bore communicates suitably for the passage of a liquid into said bore, a pair of electrodes, a suitable quantity of liquid conductor within said container, said container including means for flowing said liquid conductor into said bore and into contact with said electrodes to electrically connect said electrodes lengthwise through said bore, the shape and arrangement of said container and control tube being such that liquid conductor expelled from said control tube by an overload will be prevented from reconnecting said electrodes except upon operation of said means and; means to minimize arcing in said bore when current is interrupted therein.

5. A liquid conductor current limiting circuit controller including: a control tube made of heat resisting insulation and having a current

limiting bore therewithin, a casing surrounding said control tube and forming an expansion chamber with which said bore communicates suitably for the passage of a liquid into said bore, 5 a pair of electrodes, a suitable quantity of liquid conductor within said container, said container including means for flowing said liquid conductor into said bore and into contact with said electrodes to electrically connect said electrodes lengthwise through said bore, the shape and arrangement of said container and control tube being such that liquid conductor expelled from said control tube by an overload will be prevented from reconnecting said electrodes except upon 10 operation of said means; and means to minimize arcing in said bore when current is interrupted therein, comprising an arc by-pass.

6. A liquid conductor current limiting circuit controller including: a control tube made of heat 20 resisting insulation and having a current limiting bore therewithin, a casing surrounding said control tube and forming an expansion chamber with which said bore communicates suitably for the passage of a liquid into said bore, a pair of electrodes, a suitable quantity of liquid conductor within said container, said container including means for flowing said liquid conductor into said bore and into contact with said electrodes to electrically connect said electrodes lengthwise 25 through said bore, the shape and arrangement of said container and control tube being such that liquid conductor expelled from said control tube by an overload will be prevented from reconnecting said electrodes except upon operation 30 of said means; and means to minimize arcing in said bore when current is interrupted therein comprising an arc by-pass electrically connected to one electrode and located so close to the other electrode that an arc will jump more readily between the last named electrode and said by-pass than between said last named electrode and the liquid conductor electrically connected to the other electrode. 35

7. A liquid conductor current limiting circuit controller including: a control tube made of heat 40 resisting insulation and having a current limiting bore therewithin, a casing surrounding said control tube and forming an expansion chamber with which said bore communicates suitably for the passage of a liquid into said bore, a pair of electrodes, a suitable quantity of liquid conductor within said container, said container including means for flowing said liquid conductor into said bore and into contact with said electrodes to electrically connect said electrodes lengthwise 45 through said bore, the shape and arrangement of said container and control tube being such that liquid conductor expelled from said control tube by an overload will be prevented from reconnecting said electrodes except upon operation of said means; and means to minimize arcing in said bore when current is interrupted therein comprising an arc by-pass electrically connected to one electrode and located so close to the other electrode that an arc will jump more readily between the last named electrode and said by-pass than between said last named electrode and the liquid conductor electrically connected to the other electrode, and arc restricting means offering such resistance to the arcing to said by-pass that the arcing is not self-sustaining. 50

8. A liquid conductor current limiting circuit controller including: a control tube made of heat 55 resisting insulation and having a current limiting bore therewithin, a casing surrounding said con-

trol tube and forming an expansion chamber with which said bore communicates suitably for the passage of a liquid into said bore, a pair of electrodes, a suitable quantity of liquid conductor within said container, said container including means for flowing said liquid conductor into said bore and into contact with said electrodes to electrically connect said electrodes lengthwise through said bore, the shape and arrangement of said container and control tube being such that liquid conductor expelled from said control tube by an overload will be prevented from reconnecting said electrodes except upon operation of said means; and means to minimize arcing in said bore when current is interrupted 10 therein comprising an arc by-pass electrically connected to one electrode and located so close to the other electrode that an arc will jump more readily between the last named electrode and said by-pass than between said last named electrode and the liquid conductor electrically connected to the other electrode, and arc restricting means offering such resistance to the arcing to said by-pass that the arcing is not self-sustaining, said means comprising insulation for covering all but 15 a small exposed area of the part of said by-pass which would otherwise be accessible to an arc. 20

9. A liquid conductor current limiting circuit controller including: a control tube made of heat 25 resisting insulation and having a current limiting bore therewithin, a casing surrounding said control tube and forming an expansion chamber with which said bore communicates suitably for the passage of a liquid into said bore, a pair of electrodes, a suitable quantity of liquid conductor 30 within said container, said container including means for flowing said liquid conductor into said bore and into contact with said electrodes to electrically connect said electrode lengthwise through said bore, the shape and arrangement of said 35 container and control tube being such that liquid conductor expelled from said control tube by an overload will be prevented from reconnecting said electrodes except upon operation of said means; and means to minimize arcing in said bore when 40 current is interrupted therein comprising an arc by-pass electrically connected to one electrode and located so close to the other electrode that an arc will jump more readily between the last named electrode and said by-pass than between 45 said last named electrode and the liquid conductor electrically connected to the other electrode, and arc restricting means offering such resistance to the arcing to said by-pass that the arcing is not self-sustaining, said arc restricting means 50 comprising a resistance in said by-pass. 55

10. A liquid conductor current limiting circuit controller including: a control tube made of heat 60 resisting insulation and having a current limiting bore therewithin, a casing surrounding said control tube and forming an expansion chamber with which said bore communicates suitably for the passage of a liquid into said bore, a pair of electrodes, a suitable quantity of liquid conductor within said container, said container including means for flowing said liquid conductor into said bore and into contact with said electrodes to electrically connect said electrodes lengthwise through said bore, the shape and arrangement of said container and control tube being such 65 that liquid conductor expelled from said control tube by an overload will be prevented from reconnecting said electrodes except upon operation of said means; and means to minimize arcing in said bore when current is interrupted therein 70 75

comprising an arc by-pass electrically connected to one electrode and located so close to the other electrode and said by-pass that an arc will jump more readily between the last named electrode and said by-pass than between said last named electrode and the liquid conductor electrically connected to the other electrode, and arc restricting means offering such resistance to the arcing to said by-pass that the arcing is not self-sustaining, said arc restricting means comprising a resistance in said by-pass and insulation for covering all but a small exposed area of the part of said by-pass which would otherwise be accessible to an arc.

11. A liquid conductor current limiting circuit controller, including: a control unit including a control tube made of heat resisting insulation and having a current limiting bore therewithin, a casing substantially surrounding said control unit and forming an expansion chamber with which said bore communicates at both ends, a pair of electrodes, a suitable quantity of liquid conductor within said container, said controller including means for flowing said liquid conductor into said bore and into contact with said electrodes to electrically connect said electrodes lengthwise through said bore, the shape and arrangement of said container and control unit being such that liquid conductor expelled from said control tube by an overload will be prevented from reconnecting said electrodes except upon operation of said means; said control unit including a metallic jacket surrounding and reinforcing said control tube, and a metallic feed tube integrally secured to said jacket and communicating with said bore.

12. A liquid conductor current limiting circuit controller, including: a control unit including a control tube made of heat resisting insulation and having a current limiting bore therewithin, a casing substantially surrounding said control unit and forming an expansion chamber with which said bore communicates at both ends, a pair of electrodes, a suitable quantity of liquid conductor within said container, said controller including means for flowing said liquid conductor into said bore and into contact with said electrodes to electrically connect said electrodes lengthwise through said bore, the shape and arrangement of said container and control unit being such that liquid conductor expelled from said control tube by an overload will be prevented from reconnecting said electrodes except upon operation of said means; said control unit including a metallic jacket surrounding and reinforcing said control tube, and a metallic feed tube integrally secured to said jacket and communicating with said bore, said feed tube being butt-welded to said jacket.

13. A liquid conductor current limiting circuit controller, including: a control unit including a control tube made of heat resisting insulation and having a current limiting bore therewithin, a casing substantially surrounding said control unit and forming an expansion chamber with which said bore communicates at both ends, a pair of electrodes, a suitable quantity of liquid conductor within said container, said controller including means for flowing said liquid conductor into said bore and into contact with said electrodes to electrically connect said electrodes lengthwise through said bore, the shape and arrangement of said container and control unit being such that liquid conductor expelled from said control tube by an overload will be prevented from re-

connecting said electrodes except upon operation of said means; said control unit including a metallic jacket surrounding and reinforcing said control tube, and a metallic feed tube integrally secured to said jacket and communicating with said bore and extending from said jacket at an angle to said bore.

14. A liquid conductor current limiting circuit controller, including: a control unit including a control tube made of heat resisting insulation and having a current limiting bore therewithin, a casing substantially surrounding said control unit and forming an expansion chamber with which said bore communicates at both ends, a pair of electrodes, a suitable quantity of liquid conductor within said container, said controller including means for flowing said liquid conductor into said bore and into contact with said electrodes to electrically connect said electrodes lengthwise through said bore, the shape and arrangement of said container and control unit being such that liquid conductor expelled from said control tube by an overload will be prevented from reconnecting said electrodes except upon operation of said means; said control unit including a metallic jacket surrounding and reinforcing said control tube, and a metallic feed tube integrally secured to said jacket and communicating with said bore, said feed tube being butt-welded to said bore and extending from said jacket at an angle to said bore.

15. A liquid conductor current limiting circuit controller, including: a control unit including a control tube made of heat resisting insulation and having a current limiting bore therewithin, a casing substantially surrounding said control unit and forming an expansion chamber with which said bore communicates at both ends, a pair of electrodes, a suitable quantity of liquid conductor within said container, said controller including means for flowing said liquid conductor into said bore and into contact with said electrodes to electrically connect said electrodes lengthwise through said bore, the shape and arrangement of said container and control unit being such that liquid conductor expelled from said control tube by an overload will be prevented from reconnecting said electrodes except upon operation of said means; said control unit including a metallic jacket surrounding and reinforcing said control tube, and a metallic feed tube integrally secured to said jacket and communicating with said bore, and insulation surrounding the portions of said jacket close to the electrode on the opposite side of said control tube from said feed tube.

16. A liquid conductor current limiting circuit controller, including: a control unit including a control tube made of heat resisting insulation and having a current limiting bore therewithin, a casing substantially surrounding said control unit and forming an expansion chamber with which said bore communicates at both ends, a pair of electrodes, a suitable quantity of liquid conductor within said container, said controller including means for flowing said liquid conductor into said bore and into contact with said electrodes to electrically connect said electrodes lengthwise through said bore, the shape and arrangement of said container and control unit being such that liquid conductor expelled from said control tube by an overload will be prevented from reconnecting said electrodes except upon operation of said means; said control unit including a metallic jacket surrounding and reinforcing said control

tube, and a metallic feed tube integrally secured to said jacket and communicating with said bore, and insulation surrounding the portions of said jacket close to the electrode on the opposite side 5 of said control tube from said feed tube, said insulation comprising a heat resisting insulating material wrapped around said jacket.

17. A liquid conductor current limiting circuit controller, including: a control unit including a 10 control tube made of heat resisting insulation and having a current limiting bore therewithin, a casing substantially surrounding said control unit and forming an expansion chamber with which 15 said bore communicates at both ends, a pair of electrodes, a suitable quantity of liquid conductor within said container, said controller including means for flowing said liquid conductor into said bore and into contact with said electrodes to 20 electrically connect said electrodes lengthwise through said bore, the shape and arrangement of said container and control tube being such that liquid conductor expelled from said control tube by an overload will be prevented from reconnecting said electrodes except upon operation of said 25 means, said controller being characterized by the fact that the control tube is formed of a particular non-porous material and that the liquid conductor and the elements with which it comes in contact and by which it may become contaminated are substantially free of any substances 30 which would have a chemical reaction with said particular material of which the control tube is made under the conditions of their contact.

18. A liquid conductor current limiting circuit controller including: a control tube made of heat 25 resisting insulation and having a current limiting bore therewithin, a casing surrounding said control tube and forming an expansion chamber with which 30 said bore communicates suitably for the passage of a liquid into said bore, a pair of electrodes, a suitable quantity of liquid conductor within said container, said container including means for flowing said liquid conductor into said bore and into contact with said electrodes to 35 electrically connect said electrodes lengthwise through said bore, the shape and arrangement of said container and control tube being such that liquid conductor expelled from said control tube by an overload will be prevented from reconnecting said electrodes except upon operation of 40 said means; said controller being characterized by the fact that the control tube is composed chiefly of talc which has been kilned at a temperature in excess of 1900° F.

19. A liquid conductor current limiting circuit controller manually operable as a switch including: a casing, a control unit, a pair of electrodes located within said casing, said electrodes being 45 electrically connected to controller terminals and being electrically connectible by liquid conductor in said control unit, said control unit being constructed to cause said mercury to flow therefrom and interrupt the flow of current between 50 said electrodes both in response to an overload and in response to manual operation of said controller, and a space discharge tube connected across said controller terminals, said discharge tube being operable at the voltage of the circuit controlled by said controller, and contact means for disconnecting said tube when said controller is manually operated to disconnect the electrodes 55 therein.

20. A liquid conductor current limiting circuit controller including: a control tube made of heat 60 resisting insulation and having a current limiting bore therewithin, a casing surrounding said control tube and forming an expansion chamber with which 65 said bore communicates suitably for the passage of a liquid into said bore, a pair of electrodes, a suitable quantity of liquid conductor within said container, said container including means for flowing said liquid conductor into 70 said bore and into contact with said electrodes to electrically connect said electrodes lengthwise through said bore, the shape and arrangement of said container and control tube being such that liquid conductor expelled from said control tube by an overload will be prevented from reconnecting 75 said electrodes except upon operation of said means; said controller being characterized by the fact that the control tube is formed of a ceramic substance composed principally of silicate of magnesia and silicate of aluminum.

21. A liquid conductor current limiting circuit controller including: a control tube made of heat 80 resisting insulation and having a current limiting bore therewithin, a casing surrounding said control tube and forming an expansion chamber with which 85 said bore communicates suitably for the passage of a liquid into said bore, a pair of electrodes, a suitable quantity of liquid conductor within said container, said container

bore therewithin, a casing surrounding said control tube and forming an expansion chamber with which 90 said bore communicates suitably for the passage of a liquid into said bore, a pair of electrodes, a suitable quantity of liquid conductor within said container, said container including means for flowing said liquid conductor into said bore and into contact with said electrodes to 95 electrically connect said electrodes lengthwise through said bore, the shape and arrangement of said container and control tube being such that liquid conductor expelled from said control tube by an overload will be prevented from reconnecting 100 said electrodes except upon operation of said means, said controller being characterized by the fact that the control tube is formed of a particular non-porous material and that the liquid conductor and the elements with which it comes in contact and by which it may become contaminated are substantially free of any substances 105 which would have a chemical reaction with said particular material of which the control tube is made under the conditions of their contact.

22. A liquid conductor current limiting circuit controller including: a control tube made of heat 110 resisting insulation and having a current limiting bore therewithin, a casing surrounding said control tube and forming an expansion chamber with which 115 said bore communicates suitably for the passage of a liquid into said bore, a pair of electrodes, a suitable quantity of liquid conductor within said container, said container including means for flowing said liquid conductor into said bore and into contact with said electrodes to 120 electrically connect said electrodes lengthwise through said bore, the shape and arrangement of said container and control tube being such that liquid conductor expelled from said control tube by an overload will be prevented from reconnecting 125 said electrodes except upon operation of said means; said controller being characterized by the fact that the control tube is composed chiefly of talc which has been kilned at a temperature in excess of 1900° F.

23. A liquid conductor current limiting circuit controller including: a control tube made of heat 130 resisting insulation and having a current limiting bore therewithin, a casing surrounding said control tube and forming an expansion chamber with which 135 said bore communicates suitably for the passage of a liquid into said bore, a pair of electrodes, a suitable quantity of liquid conductor within said container, said container including means for flowing said liquid conductor into 140 said bore and into contact with said electrodes to electrically connect said electrodes lengthwise through said bore, the shape and arrangement of said container and control tube being such that liquid conductor expelled from said control tube by an overload will be prevented from reconnecting 145 said electrodes except upon operation of said means; said controller being characterized by the fact that the control tube is formed of a ceramic substance composed principally of silicate of magnesia and silicate of aluminum.

24. A liquid conductor current limiting circuit controller including: a control tube made of heat 150 resisting insulation and having a current limiting bore therewithin, a casing surrounding said control tube and forming an expansion chamber with which 155 said bore communicates suitably for the passage of a liquid into said bore, a pair of electrodes, a suitable quantity of liquid conductor within said container, said container

- including means for flowing said liquid conductor into said bore and into contact with said electrodes to electrically connect said electrodes lengthwise through said bore, the shape and arrangement of said container and control tube being such that liquid conductor expelled from said control tube by an overload will be prevented from reconnecting said electrodes except upon operation of said means; said controller being characterized by the fact that the control tube is formed of a ceramic substance composed principally of silicate of magnesia and silicate of aluminum with the silicate of magnesia predominating in quantity.
15. 24. A liquid conductor current limiting circuit controller including: a control tube made of heat resisting insulation and having a current limiting bore therewithin, a casing surrounding said control tube and forming an expansion chamber with which said bore communicates suitably for the passage of a liquid into said bore, a pair of electrodes, a suitable quantity of liquid conductor within said container, said container including means for flowing said liquid conductor into said bore and into contact with said electrodes to electrically connect said electrodes lengthwise through said bore, the shape and arrangement of said container and control tube being such that liquid conductor expelled from said control tube by an overload will be prevented from reconnecting said electrodes except upon operation of said means; said controller being characterized by the fact that the male portion is substantially fully shrunk as by baking, while the female portion is materially less completely shrunk, and of such size that if fully shrunk it would be too small to receive the male portion.
20. 25. A liquid conductor current limiting circuit controller manually operable as a switch including: a casing, a control unit, a pair of electrodes located within said casing, said electrodes being electrically connected to controller terminals and being electrically connectible by liquid conductor in said control unit, said control unit being constructed to cause said mercury to flow therefrom and interrupt the flow of current between said electrodes both in response to an overload and in response to manual operation of said controller, means for connecting a space discharge tube across said controller terminals, and contact means for disconnecting said tube when said controller is manually operated to disconnect the electrodes therein.
25. 26. As an article of manufacture, an unfinished liquid conductor current limiting circuit controller including: a control tube made of heat

STANLEY S. GREEN.
